UNITED STATES PATENT OFFICE.

JOSEPH H. MAILHOT, OF DETROIT, MICHIGAN.

STEAM-TRAP.

1,203,639.

Specification of Letters Patent.

Patented Nov. 7, 1916.

Application filed June 26, 1915. Serial No. 36,588.

To all whom it may concern:

Be it known that I, JOSEPH H. MAILHOT, citizen of the United States, residing at Detroit, county of Wayne, State of Michigan, have invented a certain new and useful Improvement in Steam-Traps, and declare the following to be a full, clear, and exact description of the same, such as will enable others skilled in the art to which it pertains to make and use the same, reference being had to the accompanying drawings, which form a part of this specification.

My invention relates to an improvement in steam traps or water feeders for boilers, shown in the accompanying drawings and more particularly pointed out in the following specification and claims.

One object of my invention is to reduce the cost and simplify the general construction of a tilting trap of a type embodying two oscillating, alternately filling and discharging water chambers, adapted to deliver water to a boiler, or to return the water of condensation from a heating system back to the boiler against the steam pressure therein.

One feature of the invention consists in the peculiar construction of the valve controlling the delivery of water to the respective tanks and its alternate discharge therefrom into the boiler, upon the alternate delivery through a steam valve of like construction of boiler pressure to the tanks.

Another feature of the invention consists in the means employed to cushion the impact of the respective tanks produced by the alternate tilting of the latter.

Other advantages and improvements will hereafter appear.

In the drawings accompanying this specification:—Figure 1, is a longitudinal vertical section of the device, on line 1—1 of Fig. 5. Fig. 2, is an end elevation, with the valve for alternately delivering the water to and from the tanks in section, (taken on line 2—2 of Fig. 3) showing also in section the dash-pots receiving the alternate impact of the tanks. Fig. 3, is a fragmentary detail, indicating in horizontal section the construction of the water or steam valve (the valves being of similar construction) controlling the alternate delivery and discharge of water or steam to and from the respective tanks, the arrows indicating water or steam

entering the right hand tank and discharging from the left hand tank. Fig. 4, is a view similar to Fig. 3, with the oscillating casing shifted so that its respective ports are in position to deliver water or steam to the left hand tank and to discharge the water or steam previously delivered from the right hand tank, as indicated by the arrows. Fig. 5, is a cross-sectional view with pipes H, and H' broken away and the valve casing J, removed, showing the tanks in the act of tilting, as indicated by the arrow and before the right hand tank is deposited in its respective dash-pot cradle. Fig. 6, is a perspective view of a packing ring surrounding the ports of the valves.

Referring now to the letters of reference placed upon the drawings:—A, and A', are tilting twin tanks supported from below at one end by the water pipe connections B and B', in turn connected with an oscillating water valve chamber C.

D, is a stationary water valve incased within the oscillating chamber C, having two pairs of ports d, d', and d², d³,—one of each pair of ports being adapted to establish a connection between the inlet pipe F, leading from the heating system and one of the respective tanks A and A', through the pipes B and B';—the other port of each pair of ports serving to connect the respective tanks A and A', through the pipes B and B', with the pipe G, leading to a boiler (not shown) or other place of discharge, upon the ports c, c', and c², c³, of the oscillating valve chamber C, registering with the ports d, d', and d², d³, as a result of the tilting action of the tanks through the alternate filling and discharging of the latter. The twin tanks A and A', are also supported at their opposite ends by steam pipe connections H and H', which extend upwardly within the tanks above the predetermined water level therein.

I, indicates a stationary steam valve having two pairs of ports, similar in construction to the water valve D.

J, is an oscillating valve chamber inclosing the valve I, having two pairs of ports, the construction being similar to the oscillating water chamber C.

The ports in the valve I, co-act with the ports in the oscillating chamber J, to alternately establish a steam connection between

the respective pipes H and H', extending above the water level in the tanks A and A', and the pipe K leading from the boiler (not shown); and between the tanks and the exhaust pipe L, fitted with a check valve L². (See Fig. 1.) Thus through the alternate tilting of the tanks due to the admission of water thereto, boiler pressure is recurrently established in the respective tanks that the water therein contained may pass by gravity to the boiler, while the pressure in the previously discharged tank is alternately exhausted that the water of condensation from the heating system may be admitted to the trap. The water pipe F, and the steam pipe L, respectively serve as trunnions for the oscillating tanks and are in turn supported by the hub standards F' and L', mounted upon the base plate P.

20 F², is a nipple projecting from the hub standard F', carrying a check valve F³, in line with the pipe leading from the heating system, (not shown) through which water may pass to the trap but which is adapted 25 to close against the return of water therefrom.

L², is a nipple projecting from the hub standard L', carrying the check valve L³, through which pressure in the tanks may be 30 alternately released that a fresh charge of water may be admitted to the tanks.

M, M', denote standards rising from the base plate having an arcuate shaped top, which may be fitted with roller bearings if 35 desired, to respectively receive the oscillating chambers C and J, carrying the tanks A and A'.

N, is a central standard to which is pivoted a rocking arm N', having arcuate 40 shaped ends N², to alternately receive the tanks when tilted.

O, O, denote dash-pots located at opposite ends of the base plate and pivoted thereto.

O', indicates a plunger housed in each 45 dash-pot, and O², O², are rods connecting the respective plungers with the ends of the rocking arm N'.

O³, denotes a port in the plunger for the 50 passage of oil through the latter, and O⁴, is a spring housed within each chamber, adapted to act upon the plunger.

D', denotes a packing ring (see Fig. 6) surrounding the respective port openings in the valve D.

55 D², indicate springs designed to maintain the packing rings in contact with the wall of the oscillating chamber C.

D³, designates a packing between the valve D and the flange of the annular ring D', to 60 insure a tight joint at this point.

C', indicates a brass or other bushing, lining the oscillating chambers C and J.

A², is a tie rod connecting the tanks A—A' together.

65 Having thus indicated the several parts

by reference letters, the construction and operation of the device will be readily understood. The trap is located above the boiler in the usual manner in order that the water delivered to it may pass by gravity into the 70 boiler. Suitable piping (not shown) connects the pipe F, controlled by check valve F³, with the returns from the heating system or feed water supply. Water delivered through the pipe F, enters the oscillating 75 valve chamber C, passing thence through the port d, in the valve D, and the port C, in the oscillating chamber C; out through the pipe B', into the elevated tank A', gradually filling the latter, (see Fig. 3) it being noted 80 that the port d³, is closed by the valve chamber C, (see Fig. 2) when the tank A', is in its elevated position. When a sufficient volume of water has entered the tank A', to overcome the weight of the tank A, the 85 tanks tilt on their supporting trunnions, which action cuts off the supply of water to the tank A', due to the shifting of the port c, in the oscillating water valve chamber C, with reference to the port d, in the valve 90 D—the water being delivered instead through the ports d², and c², and thence by the pipe B, to the tank A, now elevated, as will hereafter be more fully explained, while the water in the tank A', (now depressed) will pass by gravity out through the pipe B', the ports c³, d³, the pipe G, to the boiler, (see Fig. 4) as will be more fully 95 explained.

Attention is now directed to the oscillating steam valve chamber J, through which steam may pass from the boiler to the respective tanks to establish boiler pressure therein. As previously stated, the construction of the steam valve and its co-acting 100 parts is similar to that of the water valve and its co-acting parts, therefore upon the tank A', tilting under the weight of water contained therein, steam passing through the pipe K, is delivered through ports in 105 110 the valve I, and chamber J, to the pipe H and conveyed thereby into the tank A' above the water level therein, establishing boiler pressure within the tank—and thereby permitting the water to pass by gravity out 115 through the pipe B', through the port c³, through the port d³, through the port G, to the boiler.

While the tank A' is discharging its 120 contents into the boiler, the tank A is being filled by the returns from the heating system or other source of supply and as soon as the weight of water in the tank A, overcomes the weight of the tank A', the tanks will tilt back to their former position, thereby reversing the water and steam control valves. Steam will now be admitted to the tank A (see Fig. 4), establishing boiler pressure within, permitting the water therein to pass by gravity out through the ports c³, 125 130

and d' , to the boiler as previously described, while any steam remaining in the now elevated tank A' , will be released by the steam valve into the exhaust pipe L' , passing thence through the check valve I^3 , to the atmosphere, or to a sewer or other connection;—the object being to free the tank of pressure that water may again enter the tank. The jar which might otherwise result from tilting the tanks is absorbed through the rocking arm N' , co-acting with the dash-pots O, O , the plungers of which are respectively linked to the ends of the rocking arm. The dash-pots are filled with oil and it will be obvious that upon the tanks alternately striking opposite ends of the arm N , it will cause the latter to rock, thereby actuating the pistons, forcing the oil in the chambers to pass back and forth through the ports O^3 , as the pistons alternately reciprocate, checking the force of the impact which is further relieved by the spring located within each dash-pot chamber.

Having thus described my invention, what I claim is:—

1. In an apparatus of the character described, a base plate, a pair of oscillating valve chambers spaced apart and supported upon the base, a pair of tanks, pipe connection between the oscillating valve chambers and the tanks, each valve chamber having two pair of ports, each pair of ports communicating with one of the pipes leading to the tanks, and a stationary valve housed in each oscillating valve chamber having two pair of ports adapted to co-act with the ports of the respective valve chambers, whereby water and boiler pressure may be delivered alternately to the respective tanks and discharged therefrom.

2. In an apparatus of the character described, a base plate, a pair of oscillating valve chambers spaced apart and supported upon the base, a pair of tanks, pipe connection between the oscillating valve chambers and the tanks, each valve chamber having two pair of ports, each pair of ports communicating with one of the pipes leading to the tanks, means for conveying water to one of the oscillating valve chambers for delivery to the tanks, means for conveying boiler pressure to the other oscillating valve chamber for delivery to the tanks, means for conveying the water discharged from the tanks to the boiler, and means for discharging the boiler pressure from the tanks when released through the operation of one of the oscillating valve chambers.

3. In an apparatus of the character described, a base, a pair of oscillating valve chambers spaced apart and supported upon the base, a pair of tanks, pipe connections between the oscillating valve chambers and the respective tanks, each of said oscillating

valve chambers provided with two pair of ports, each pair of ports communicating with one of the pipes leading to the tanks, a stationary valve housed within each oscillating valve chamber having two pair of ports adapted to co-act with the ports of its respective oscillating valve chamber to establish communication respectively with the boiler and with a water supply pipe, and between the steam space of the boiler and exhaust pipe, said valves being operably connected with the tanks whereby one of the valves will alternately deliver and discharge water into and from the respective tanks while the other valve admits steam into one tank while exhausting steam from the other tank, a pipe for delivering water to one of the oscillating valve chambers, a check valve to close against the return of said water, means for delivering the water from the respective tanks to the boiler under the control of the oscillating valve chamber, an exhaust pipe for delivering steam from the respective chambers, under control of the other oscillating valve chamber, and a check valve to close against the return of the exhaust, substantially as described.

4. In a device of the character described, a base plate, a pair of oscillating valve chambers supported from the base, a pair of tanks, pipe connections between the oscillating valve chambers and the tanks adapted to support the tanks and to provide communication between the valve chambers and the tank, each of said oscillating valve chambers having two pairs of ports, a stationary valve housed in each of the oscillating chambers, having two pairs of ports co-acting with the ports of the respective oscillating chambers inclosing the valves, means for conveying water to said chamber for alternate delivery thereby to the tanks, means for delivering steam from the boiler through the other oscillating valve chamber to the tanks alternately, means for cushioning the impact of the tilting tanks, comprising a rocking arm supported by the base having ends adapted to alternately receive the tanks, a pair of disconnected fluid chambers spaced apart and pivoted to the base, a plunger adapted to reciprocate in each of the fluid chambers perforated for the passage of the fluid, and connecting rods engaging the plunger and the respective ends of the rocking arm.

5. In an apparatus of the character described, a base plate, a pair of oscillating valve chambers supported from the base, a pair of tanks, pipe connection between the oscillating valve chambers and the tanks, each valve chamber having two pair of ports, each pair of ports communicating with one of the pipes leading to the tanks, a stationary valve housed in each oscillating valve chamber having two pair of ports

adapted to co-act with the ports of the respective valve chambers, whereby water and boiler pressure may be delivered alternately to the respective tanks and discharged therefrom, an adjustable packing ring surrounding each of said ports, having an inwardly projecting flange extending into the stationary valve, and resilient elements to force

the ring in contact with the wall of the valve chamber.

In testimony whereof, I sign this specification in the presence of two witnesses.

JOSEPH H. MAILHOT.
